UNITED STATES PATENT OFFICE

DONALD A. EDDY, OF CINCINNATI, OHIO

DESIGN FOR A MIRROR

Application filed March 14, 1932. Serial No. 43,188. Term of patent 3½ years.

To all whom it may concern:

Be it known that I, DONALD A. EDDY, a citizen of the United States, residing at Cincinnati, in the county of Hamilton and State of Ohio, have invented a new, original, and ornamental Design for Mirror, of which the following is a specification, reference being had to the accompanying drawing, forming a part thereof.

The figure is a perspective view of the mirror showing my new design.

I claim:

The ornamental design for a mirror as shown.

DONALD A. EDDY.
